CLAIM

The ornamental design for a flexible wrench for narrow spaces, as shown and described.

DESCRIPTION

FIG. 1 is a front view of a flexible wrench for narrow spaces showing my new design;

FIG. 2 is an enlarged partial view thereof;

FIG. 3 is an alternate left side view thereof, the alternate right side view being a mirror image;

FIG. 4 is a bottom view thereof;

FIG. 5 is a top view thereof;

FIG. 6 is an alternate perspective view thereof; and,

FIG. 7 is another perspective view thereof.
